UNITED STATES PATENT OFFICE.

CHARLES H. RIETH, OF ST. LOUIS, MISSOURI, ASSIGNEE TO ROBERT E. RENFRO, OF CARBONDALE, ILLINOIS.

COMBINATION GAME-BLOCKS.

956,827.

Specification of Letters Patent. Patented May 3, 1910.

Application filed June 22, 1907. Serial No. 380,362.

To all whom it may concern:

Be it known that I, CHARLES H. RIETH, a citizen of the United States, and resident of St. Louis, Missouri, have invented certain new and useful Improvements in Combination Game-Blocks, of which the following is a specification containing a full, clear, and exact description, reference being had to the accompanying drawings, forming a part hereof.

My invention relates to combination game blocks, and comprises four sets of suits of blocks, on the faces of which appear symbols, letters, and numerals, and with which blocks can be played all known games of cards and dominoes, and many new combinations thereof.

My invention consists in certain features of novelty hereinafter shown, described, and claimed.

In the drawings:—Figure 1 is a perspective view of one of the game blocks; Fig. 2 is a transverse section taken on the line 2—2 of Fig. 1; Fig. 3 is a view of the faces of the blocks comprising the diamond suit; Fig. 4 is a view of the faces of the blocks comprising the heart suit; Fig. 5 is a view of the faces of the blocks comprising the club suit; Fig. 6 is a view of the faces of the blocks comprising the spade suit.

The game blocks 1 as shown consist of fifty-six pieces, constructed of any suitable material, rectangular in form, and similar to the blocks used in the game of dominoes.

Each block 1 is provided on its face with a raised border 1^a, and a raised dividing line 2, thus forming two depressions of equal area and depth in which are inserted or applied sections 3, on which are provided the letters, numerals, and symbols designating the various suits or characters of the game set.

Appearing on the sections, to the left of the dividing line on fourteen of the blocks is a diamond shaped figure 3^a, which is colored or printed in red to correspond with the diamond suit of a pack of cards.

Appearing on the centers of the sections 3, to the right of the dividing lines of thirteen of this set of blocks are the letters and figures,—A, 2, 3, 4, 5, 6, 7, 8, 9, 10, J, Q, K; and appearing on the right hand section 3 of the remaining block of this suit is a diamond shaped figure; and thus this particular set of blocks represents respectively

the ace, deuce, three, four, five, six, seven, eight, nine, ten, jack, queen, and king of the diamond suit of a pack of cards, together with a double diamond, which may be used as a joker in playing card games, or for a combination or key piece when playing games which are combinations of cards and dominoes. A second set of fourteen blocks have their faces formed in a manner similar to the diamond set of cards just described, 65 said second set representing the heart suit of a pack of playing cards; and the faces of the third and fourth sets of blocks are formed to correspond with the club and spade suits, and which latter two sets are 70 printed or appear in black.

The faces of the blocks are recessed to receive the sections 3 in order that the numerals, letters, and symbols appearing on said sections will not become worn off or 75 discolored while the blocks are in use, as the raised edges of the blocks prevent the edges of the sections 3 from coming in contact with the table.

It will be readily understood that with a 80 set of the blocks formed as herein described, all games ordinarily played with games or dominoes may be played with said blocks, and new games, or combinations of cards and domino games, may also be played. 85

The four blocks having the double diamonds, hearts, clubs, and spades may be utilized as jokers, thereby providing new possibilities in card games, and constitute the keys or connecting links for adapting 90 these blocks to the playing of all domino games, viz., that instead of laying and matching dots and blanks, as is done with ordinary dominoes, with my improved set a heart is matched to a heart, a spade to a 95 spade, a diamond to a diamond, and a club to a club, using the double, symbols for the crosses. Furthermore, all letters and figures on the opposite ends of my improved game pieces will match one another, regardless of suit or color. 100

Euchre, whist, pedro, and all other card games may be played with my improved game pieces precisely as with cards, except that the shuffling or mixing is done as with 105 dominoes. All domino games are played with my improved game pieces with the adaptation as above noted.

It will be seen from the foregoing description that it is only by the employment of the 110

four blocks having the double emblems on their faces, to-wit, double hearts, double diamonds, double clubs, and double spades, is it possible to adapt a game set to the playing of domino games, and the creation of new games which may be a combination of both cards and dominoes.

10 The blocks with which the games are played are conveniently handled, and are easily and quickly shuffled by being placed face downward upon the table, and moved about.

I claim:—

15 The herein described combination game blocks, comprising a set of fifty-six blocks divided into four equal sets of fourteen each, namely, a suit of diamonds, a suit of hearts, a suit of clubs, and a suit of spades, the faces of all the blocks being of uniform color 20 and the faces of all the blocks being divided into two spaces and thirteen blocks of each suit being provided respectively in the spaces on one side of the dividing line with diamond, heart, club and spade symbols printed

in a color in contrast to the faces of the 25 blocks, and the opposite spaces on the faces of the four suits of thirteen blocks provided with the letters and numbers A, 2, 3, 4, 5, 6, 7, 8, 9, 10, J, Q, K, printed in the same color as the symbols in the opposite spaces on the 30 same blocks, but in contrasting color to the face of the block, and the remaining or fourteenth block of each suit being provided on its front face with respectively a double diamond, a double heart, a double club, and 35 a double spade symbol, printed in the same respective color as the symbols and characters appearing on the thirteen blocks of each suit and the said double symbols appearing on the fourteenth block of each suit being 40 separated by a dividing line.

In testimony whereof, I have signed my name to this specification, in presence of two subscribing witnesses.

CHARLES H. RIETH
